UNITED STATES PATENT OFFICE

JAMES DAVIS, OF PAWTUCKET, RHODE ISLAND.

IMPROVEMENT IN MACHINES FOR CUTTING RESINOUS GUMS.

Specification forming part of Letters Patent No. 175,044, dated March 21, 1876; application filed August 9, 1875.

To all whom it may concern:

Be it known that I, JAMES DAVIS, of Pawtucket, in the county of Providence and State of Rhode Island, have invented certain new and useful Improvements in Machinery for Cutting Resinous Gums used in the arts of dyeing and tanning, of which the following is a specification:

Resinous and gummy agents used in the arts, like cutch, gambier, and japonica, are required to be cut into small pieces or shavings preparatory to the operation of extracting their coloring or other properties for which they are valuable. This operation has hitherto been performed by hand, and, from the gummy nature of the material, it is necessarily a very tedious and laborious one, and no ordinary cutting machinery is adapted to perform the work on account of the circumstance that the gum adheres to the entire surface of the cutting-knife.

My invention has resulted in a practically useful machine, which enables the operation of shaving or slicing such gums or resinous substances to be performed with entire ease and with perfect facility.

Figure 1 is a top view or plan of the machine. Fig. 2 is a side elevation. Fig. 3 is a vertical section on line $x x$, Fig. 2. Figs. 4 to 6 represent detailed parts.

The machine consists, essentially, of a reciprocating cutting-knife, a table suitably arranged for enabling the gum to be fed to the knife, and devices for clearing and lubricating the knife after each slice of gum has been cut off.

A represents the frame of the machine. B, Fig. 2, is a knife, which is attached to a frame, a , such frame being mounted in suitable guides, b , and is capable of receiving a reciprocating movement by means of the shackle-link c , connecting the knife-frame with a revolving crank or wheel, C, driven by power applied in any preferred way. The knife B may be set obliquely to the axis of the knife-frame, so as to obtain the advantage of a draw-cut, if preferred.

At right angles with the plane in which the knife reciprocates is placed an endless feeding-

table, D, the arrangement of which, relatively to the knife-frame, is shown at Fig. 3. A crank, E, enables the operator to feed forward the material to be sliced by hand, or, if preferred, the table may have imparted to it an intermittent movement by means of a pawl and ratchet gear, so as to be automatic in its operation at the proper time.

It is necessary, for the successful working of the apparatus above described, or any similar apparatus having a reciprocating cutter and a feeding-table, that there should be a means for cleaning and lubricating the knife after each cut has been made; and herein resides my improvement.

In combination with any suitable machinery for cutting slices successfully from a mass of gum, I employ a wiper, F, which is to be so constructed and arranged that it can adapt itself to the form of the knife, and, pressing against the sides of the blade, wipe from it, as the knife is completing a stroke and about commencing a new one, the adhering gum. In this instance the wiper has two wings, (shown in section at Fig. 5,) each of which is capable of vibrating upon its central longitudinal axis by means of pivot-hinges d a , Fig. 6. The inner contiguous faces of the wings are covered with sheepskin dressed with the wool on. A spring, e , Fig. 5, applied to the two wings, causes their inner faces to stand at an angle with each other, with the widest opening toward the knife, and so that, as the knife is returning after making a cut and before completing its stroke, it will enter between the wings of the wiper. The continued movement of the knife-frame past the axis of the pivoted wings causes their front edges to approach each other, and thus close upon the sides of the knife-blade and, by conforming to the shape of the same, clean it of all gum which adheres to it.

It is necessary that the knife-blade should be lubricated, preparatory to making a cut, by water or by oil, and, also, it is desirable to wet the sheepskin covering of the wiper to facilitate the removal of gum from the knife-blade. I accordingly combine with the wiper a pipe, g , Fig. 2, which is arranged to discharge a

stream of water or other suitable lubricant between the wings of the wiper, for keeping the latter wet as well as for wetting the knife. A trough, *h*, collects the escaping water and conducts it away from the machine.

I have shown in the drawings, and have described, a cutter which is made to reciprocate to and fro, because this method of working the cutter is, in my opinion, the simplest; but, instead of a reciprocating cutter, a rotary cutter may be employed having, in connection with it, a table or support for the gum to be sliced; and, in combination with such machine, a wiper, so arranged that the knife-blade shall be obliged to pass between the rubbing-cushions composing the wiper, can be used. Such structure would employ my invention.

It will be seen that, however the table and cutters may be constructed, the gum must be so presented to the cutter that the slices cut by it will be uniform in thickness, and also that it is important for saving time in the operation that the masses of gum be as large as possible, consistent with the capacity of the cutter. For these reasons it is obvious that the cutting-table should be capable of being advanced gradually and evenly toward the cutter, either in a plane at right angles to the plane in which the cutter operates, or in a plane so nearly approximating thereto as would result in the cutting of regular slices from the mass of gum. With a reciprocating cutter, as shown, the table or feeding surface would need only to be moved toward the cutter, as described, but with a rotary cutter the table would also be arranged to be moved toward the cutting-edge of the cutter, so that the latter might operate after the table had

sufficiently advanced for cutting a slice of proper thickness.

I am aware that in machines for mincing meat, &c., as heretofore constructed, reciprocating and rotary cutters have been employed in connection with clearers, which prevented the cutters from being clogged, and also in connection with rotating tables or tubs for containing the material to be minced. While such machines are well adapted for chopping or mincing, it is obvious that they are incapable of being practically employed in cutting thin and regular slices from a mass of gum.

What I claim as my invention, and desire to secure by Letters Patent, is—

1. In a machine for cutting gum into slices, the combination of a vertical slicing-cutter, which cuts a slice at each forward stroke, a wiper for clearing the blade of the cutter, and a feeding-table for supporting the gum, which is arranged to advance the gum evenly toward the cutter, substantially as described, whereby slices of regular thickness may be cut from a mass of gum, as set forth.
2. The combination of a cutter for slicing gum with a wiper, *F*, composed of hinged wings or cushions, and capable of adapting their rubbing-faces to the shape of the cutter, substantially as described.
3. The combination of a cutter, *B*, a wiper, *F*, and a pipe, *g*, for conveying water or other lubricant to the wiper, and thence to the cutters, substantially as described.

JAMES DAVIS.
